UNITED STATES PATENT OFFICE.

EDMUND H. LUNKEN, OF CINCINNATI, OHIO.

POCKET-WINDOW SCREEN.

Specification of Letters Patent. Patented Mar. 12, 1918.

1,259,115.

Application filed June 25, 1917. Serial No. 176,657.

To all whom it may concern:

Be it known that I, EDMUND H. LUNKEN, a citizen of the United States, and a resident of the city of Cincinnati, in the county of 5 Hamilton and State of Ohio, have invented in certain new and useful Improvements in 10 Pocket-Window Screens, of which the following is a full, clear, and exact description, reference being had to the accompanying drawings, forming part of this specification.

My invention relates to screening devices for pocket windows wherein more particularly there are to be two screens, both of which slide entirely up into the pocket. 15 While some of the features of my invention would be applicable with advantage to single screens, the main object in view is the provision of an arrangement of a plurality of screens capable of complete concealment 20 in an overhead window pocket.

It is the object of the structure herein to simplify to the last degree the structure and operation of pocket window screen installations of the above type, and wherein among 25 other things the screens are of the "Lunken" interlocking molding type, and have weathering devices for protection of the additional opening on the outside of the window necessary for the accommodation of the 30 screens.

In this device there is provided a spring device which not only serves as a stop for the top screen, due to its special construction, but also serves as a sufficient frictional 35 counterbalance for the screens while moving upward into the pocket. Certain improvements are provided in the weathering devices, and the channel members for the screens are designed for easy installation in 40 connection with the other parts of a window of the pocket type.

Also it should be understood that the entire structure is designed to take up the least possible amount of space, so as to be adapted 45 for installation in houses using standard construction without any essential modification.

The above objects and advantages and other improvements which will be noted I 50 accomplish by that certain construction and

arrangement of parts to be hereinafter more specifically pointed out and claimed.

In the drawings,

Figure 1 is a central longitudinal section, taken through a window embodying my invention.

Fig. 2 is a detail perspective of the screen guide means.

Fig. 3 is a detail perspective of the corner of the pocket in a window showing the 60 spring stop feature of my invention.

Fig. 4 is a detail perspective showing the means whereby this spring retains the upper screen member in its normal position in the 65 window.

Fig. 5 is another detail perspective showing the intermediate spring stop.

Fig. 6 is a detail perspective view of an alternative form of construction of the outside.

The window has side stiles 1, 1, a sill 2 and a wall pocket 3. There are shown two sashes, an upper sash 4 and a lower sash 5, both of which are adapted to slide up into the pocket. The two sashes are separated 75 by a parting strip 6, and are provided with a special weight pulley device 7. These parts form no part of my present invention, except in so far as the weather joint between the upper rail of the upper sash 4 and the 80 screen device is concerned.

There are two screens shown in the drawings, a lower screen 8 and an upper screen 9. The screens are formed of solid metal frame pieces 10, with wire soldered to them, although this forms no part of the invention. To facilitate the passing of the moldings and the provision of close joints in connection with the weathering they are made of a metal piece which is semioval in cross section, as shown.

The lower screen is provided with an angle plate 11 across the bottom, which rests on the sill and acts as a shoulder for engagement with the outer wall of the pocket as 95 will be described, and the lower screen is also provided with an extending strip 12 which lies between the two moldings of the upper screen when the device is assembled, so as to form an interlock and permit the lower 100

screen to push up and pull down the upper screen when said former screen is operated.

The wall pocket, which is located overhead, and has an outside wall 13, which is faced with a special shaped molding 14, that confines between it and the wall 13 a piece of weathering material 14^a such as felt. This molding has a longitudinal bead 15 which may, if desired, be used as an additional weather joint, and beneath the bead the molding is cut away to form a shoulder for abutment of the angle plate 11, when the lower screen is pushed up into the pocket.

The guide for the screens is preferably 15 a double width channel, although it could be a trackway if the screen moldings were channeled. The double channels are made up of pieces 16 of complete channel form set up into the pocket and running to the 20 top thereof, and angle pieces 17 having the inner wall only of the channel, and outer trimming strips 18 which are secured to the side of the window frame so as to somewhat overlap the angle pieces 17 and form there- 25 with the balance of the channel. The overlap provides an effective water-seal for the channel so formed.

The full channel pieces run to a point just slightly below the pocket opening, and 30 form a stop for locating laterally the position of the molding 14. They are cut away slightly just at the lower end and the stile behind them is cut out at each side to form a pocket for the movable ends of springs 35 19, which ends are crooked and lie inside said pocket and are held by the said channel pieces against springing out. (Figs. 2 and 4.)

The springs are secured in the base of the lower channel pieces, *i. e.*, the angle strips 40 17, and thus lie just below the opening of the pocket. They act as the stop for preventing the upper screen from falling too low in the window opening, a friction counter-balance for both screens, and a stop 45 for holding both screens in the pocket. The function as a counter-balance can easily be seen when it is remembered that the interlocking molding device causes both screens to pass together up into the pocket, and that they will press out against the screens during this movement and tend to hold them frictionally.

As a stop for both screens when they are 55 up in the pocket (Fig. 3), it can be seen that they will spring out to fill the channel and abut against the angle plate 11 on the lower screen, and with the parts properly set up will preserve the said angle plate in position against the shoulder beneath the bead on the outside molding 14.

For the third function, the upper screen molding is specially shaped by means of cutting it away at 20 (Fig. 4) just beneath the upper corners, thereby forming a

shoulder below the top frame piece of the 65 upper screen at both upper corners. The springs will move out when this cut-away part is reached and will thus hold the upper screens in place until they are positively released by pressing them inwardly and out 70 of the way.

The upper frame member of the upper screen is provided with a facing piece 21 which makes its molding of double width to fill the channel and slide smoothly. This 75 piece has a like oval shape to the frame proper. The bead on the top molding 14 is preferably cut away at 14^b behind the pocket channel piece so as to permit the bead to extend flush with the inside of the channel 80 wall, as well as the felt weatherstrip.

When the upper screen is lowered and held in place by the springs at each side, the weatherstrip will press against its upper frame member, and the window sash is also 85 provided with a rounded molding 22 and a weatherstrip 23 which serve a like function for the inside edges of the upper frame member. When the screens are in the pocket, this window weathering will abut against 90 the lower screen frame, which also has the rounded feature that gives possibility of closer placing of the parts without chance of the corners catching so as to prevent easy 95 operation of the parts of the window.

It can be seen that the screen channel in the window opening can easily be made of no greater depth than the parting strip between the sashes and thus that there will be no unsightly channel pieces which protrude 100 out into the range of vision through the window. The exceedingly simple spring construction with threefold function gives to this screen arrangement an inexpensiveness of construction and an ease of operation 105 which are thought very valuable and useful. By pressing in the springs, the screens can be put at almost any desired position limited only by the interlocking of the frames. To remove the screens, the outside 110 trimming strips 18 can be removed.

If it is desired to have a stop for the screens at some half way point, a spring 24 may be set in this strip 18 which will catch against the angle plate on the lower screen 115 frame.

It is not intended that the spirit of this invention should be construed as applicable only to the exact structure above described, due to my failure to mention alternative 120 structures during the description. On the contrary, it is my desire that the claims that follow be given in their construction the full advantage of the doctrine of equivalents.

By the term pocket, is meant a space beyond the normal window opening and the normal position of sashes and screens into

which the sashes and screens may slide, whether or not this be entirely inclosed between opaque walls or not.

Having thus described my invention, what I claim as new and desire to secure by Letters Patent, is:—

1. A screening device for pocket windows having an overhead pocket, the combination with a pair of screens and a guide therefor, of means for guiding the screens up into the pocket, and springs set in said guiding means for holding said screens up in the pocket and frictionally counterbalancing them in their movement in the guide.
- 10 2. A screening device for pocket windows having an overhead pocket, the combination of double width channels extending up into the pocket for guiding the screens, and springs set into the channels in a position to engage both screens and hold them up in the pocket and to frictionally engage the sides of said screens during their movement into said pocket.
- 15 3. A screening device for pocket windows having an overhead pocket, the combination of a plurality of screens having their moldings interlocked as described, a double width channel guide for the screens extending up into said pocket, and springs set into the channels to engage under the screens and hold them in the pocket and to frictionally engage the sides of the screens during their movement.
- 20 4. A screening device for pocket windows having an overhead pocket comprising guides for the screens running up into the pockets, a plurality of screens on said guides, springs extending outwardly from said guides and adapted to engage beneath the screens when in the pocket, and the upper screen thereof having means to engage the said springs on its upper edge to hold it in the normal position in the upper side of the window.
- 25 5. In a pocket window having an overhead pocket, a plurality of screens, guiding means for said screens extending up into the pocket, and means for holding the upper screen thereof in position in the upper end of the window comprising a spring, and means on the said upper screen to engage the said spring, said spring being located adjacent the pocket.
- 30 6. In a pocket window, a channel for guiding the upper screen into the pocket, a spring located in the channel and adapted to press outwardly against the screen, and said screen having a cut-away edge adjacent the top thereof to receive the spring, whereby said spring serves as a counter-balance and a stop for the screen.
- 35 7. A screening device for pocket windows having an overhead pocket, the combination of a plurality of screens double width channels extending up into the pocket for guiding the screens, and springs set into the channels in a position to engage both screens and hold them up in the pocket and to frictionally engage the sides of said screens during their movement into said pocket, the upper of said screens having cut-away corners to receive said springs when said upper screen is lowered to normal position in the upper end of the window.
- 40 8. In a pocket window, the combination of a window frame and wall pocket over it, screens mounted so as to slide entirely up into the pocket, an angle plate on the lower screen, a molding located in the mouth of the pocket, the same being cut away to form a shoulder for said plate and a weatherstrip, said molding being adapted to retain the weatherstrip between it and the frame of the window for abutment against the screens.
- 45 9. In a pocket window, the combination of sliding sashes and screens in such window, and an overhead pocket to receive said sashes and screens, said screens having rounded moldings composing their frames, and rounded moldings mounted on the upper window sash and the mouth of the pocket for contact with the screen moldings, for the purpose described.
- 50 10. In a pocket window, the combination of sliding sashes and screens in such window, and an overhead pocket to receive said sashes and screens, said screens having rounded moldings and weatherstrips composing their frames, rounded moldings mounted on the upper window sash and the mouth of the pocket for contact with the screen moldings, said moldings on the sash and pocket mouth being adapted to hold the weatherstrips also for contact with the screen moldings.
- 55 11. In a pocket window having an overhead pocket, the combination of double width channel strips in the pocket thereof, angle strips extending from said pocket channel strips to the sill of the window, removable wooden filler strips mounted in the window so as to form a third channel wall for said angle strips, and springs mounted on the base of the angle strips just below the pocket, as and for the purpose specified.
- 60 12. In a pocket window having an overhead pocket, the combination of double width channel strips in the pocket thereof, angle strips extending from said pocket channel strips to the sill of the window, removable wooden filler strips mounted in the window so as to form a third channel wall for said angle strips, and springs mounted on the base of the angle strips just below the pocket, said pocket channel strips being cut away at the lower end to receive and retain the ends of the springs, said springs having ends bent over for this purpose.

13. In a pocket window having an overhead pocket, the combination of double width channel strips in the pocket thereof, angle strips extending from said pocket channel strips to the sill of the window, removable wooden filler strips mounted in the window so as to form a third channel wall for said angle strips, screens located in the channel members, a molding located at the top of the window for a weathering for the screens, said channel strips in the pocket extending below the pocket a distance so as to form an abutment for the said molding.
14. In a pocket window having an overhead pocket, the combination of double width channel strips in the pocket thereof, angle strips extending from said pocket channel strips to the sill of the window, removable

wooden filler strips mounted in the window so as to form a third channel wall for said angle strips, said filler strips being located so as to overlap the bases of the angle strips, for the purpose described.

15. In a pocket window, the combination of a plurality of screens, guiding means to retain said screens in the window and adapted to permit same to slide into the pocket, frictional springs located adjacent the pocket space to effect a counter-balance of the screens in the pocket, and an additional spring located intermediate the pocket and the sill of the window to catch the screens and hold them in elevated position below the pocket.
